UNITED STATES PATENT OFFICE

OTTO KERSTENS, OF BREMEN, GERMANY

SAFETY PIN

Application filed May 9, 1930, Serial No. 451,138, and in Germany September 23, 1929.

The present invention relates to safety pins which possess many advantages over such pins now in use. It is well-known that such pins are actuated by elastic force, increasing 5 more and more when closing the pins and reaching the maximum amount at the moment when the free arm is just about to be hooked behind the cap. Moreover, it is important that the pin should possess a certain 10 elastic limitation of its action, because only on that condition will it be impossible for the moving arm or the stationary arm to be lifted beyond the prescribed maximum limit.

Accordingly, the present invention consists in the main of a clip embracing the eyes 15 of the pin and forming an integral whole together with the eyes and the arms. The manufacture of a pin designed in this fashion is exceedingly simple. All that is necessary 20 is to bend a piece of wire by winding it round two small pins or pegs, after which the eyes thus formed are folded together. The spring action is excellent, because—owing to the extension of the eyes into a clip—a coaxially 25 acting moment is introduced, thus ensuring that the degree of elasticity remains uniform. Whenever it is intended to secure an equal amount of spring action by means of an eye formed by more windings than one or two, 30 such an eye becomes relatively thick, because the different windings must lie on top of one another. The present invention does away with this drawback, because there will never be more than two windings on top of one another. 35

The accompanying drawings show, by way of example, how the invention works. More particularly,

Fig. 1 shows the pin with the movable arm, 40 and

Fig. 2 shows the unfinished pin after the first stage of its manufacture.

A suitable piece of wire, as shown in Figure 2, is bent around two pegs to form two 45 eyes c , d , a transverse connecting bar e , and two spaced, parallel arms a , b . The bar e is bent around the arms a at $a^{\prime\prime\prime}$, and also bent around the arm b at $b^{\prime\prime}$, which places the eyes on the inside of the vertical plane of the arms 50 a , b . There the two eyes are squeezed to-

gether to lie over each other, as shown in Figure 1. When the eyes are bent as described, the connecting bar e forms a clip around the arms a , b and prevents displacement of arms and eyes. 55

The usual pin retainer f is secured to the arm b to form a means for locking the arm a , which forms the pin proper.

From the foregoing description, it will be seen that the structure is formed from a single piece of wire, the pin retaining clip, of course, being excepted, and that the manner of bending the wire not only forms spring coils but a means for holding the coils and arms in relative position. 60 65

What I claim is:—

A safety pin comprising a pair of overlapping eyes, spaced apart arms extending from the eyes, a cross bar connecting the two eyes and extending therefrom in opposite directions toward the respective arms and bent around same to form an embracing clip around said arms, and a cap having a recess and secured to one of the arms, the recess forming a catch for reception of the free end 70 75 of the opposite arm.

In testimony whereof I affix my signature.
OTTO KERSTENS.
